UNITED STATES PATENT OFFICE.

NATHAN M. LOWER, OF PITTSBURGH, PENNSYLVANIA, ASSIGNOR, BY MESNE ASSIGNMENTS, TO THE STANDARD STOKER COMPANY INC., OF NEW YORK, N. Y., A CORPORATION OF DELAWARE.

LOCOMOTIVE STOKER.

Original application filed July 26, 1926, Serial No. 124,872. Divided and this application filed November 28, 1927. Serial No. 236,029.

This application is a division of my pending application, Serial No. 124,872, filed July 26, 1926, for improvements in locomotive stokers.

5 The invention relates to locomotive stokers of the scatter feed type, and its objects are to secure, with simplicity of construction, high efficiency and durability.

In the accompanying drawings illustrating 10 a preferred form of the invention,

Fig. 1 is a detail, central, vertical, longitudinal section of a locomotive and of the improved stoker;

Fig. 2 is a plan view partly in section on the 15 line 2—2 of Fig. 1; and

Fig. 3 is a view on the line 3—3 of Fig. 1.

At 10, there is shown a backhead of the firebox of the locomotive and, as is usual, it is hollow, constituting a water leg of the boiler.

20 A portion of the grate of the firebox is shown at 11. The deck or floor of the locomotive cab is shown at 12 and the seat for the fireman is indicated at 13.

The backhead 10 is provided with the usual 25 hand firing opening 14 and the section of the backhead immediately below this opening and extending to the mud ring 15 is offset inwardly as shown at 16. A distorted ring 17 is fitted within the backhead 10 and between 30 its inner and outer sheets and follows the contour of the opening 14 and the top of the offset section 16. The mud ring 15 is shown as distorted inwardly to follow the contour of the offset section 16.

35 The offset 16 encloses an alcove or chamber exteriorly open and at its upper end communicating with the firebox. Within this chamber, there is housed a curved fuel riser conduit 18, its upper end terminating approximately at 40 the top of the offset 16. Preferably, the upper margin of the offset 16 inclines downwardly from its juncture with the undistorted portion of the backhead, and the riser conduit 18 projects, as shown, a little above its lowest point. The riser conduit 18 is suitably 45 supported as by means of a web 19 which projects downwardly and forwardly and rests upon and is secured to the outer sheet of the offset 16. The web 19 is shown as provided 50 with lateral flanges 20, 21 which seat against the outer wall of the offset and are secured thereto by means of bolts or rivets.

The lower end of the riser conduit 18 preferably terminates approximately at the plane of the outer sheet of the backhead 10 and 55 opens backwardly and is laterally flanged as shown.

A transfer conduit 22 leading forwardly from the tender (not shown) delivers to the 60 riser conduit 18 and is attached thereto by a ball and socket joint, the outer element 23 of which is secured to the lateral flange of the riser conduit and the inner member 24 of which is in the form of a ring secured to the forward end of the transfer conduit. 65

A conveyor screw 25 housed within the conduit 22, and driven from its rearward end, in accordance with common practice, terminates at the forward end of the transfer conduit, and serves not only to move the fuel 70 therethrough, but to force it upwardly through the riser conduit 18.

A plate 26 extends laterally from the upper margin of the riser conduit 18, with which it may be cast integrally although, as shown, 75 it is preferably a separate element apertured to fit upon the riser conduit. The plate 26 is preferably level and serves as a table over which the fuel issuing from the riser conduit may be swept by steam jets issuing from the 80 nozzle 27 located on the upper surface of the plate 26 at the rearward side of the riser conduit. Suitable steam pipes, as shown, lead to the nozzle 27. The plate 26 is shown as provided with downstanding flanges 28, 28, 85 which rest upon the upper margin of the offset 16, and its upper surface may be provided with curved flanges as 29, suitably disposed and shaped to guide a portion of the fuel to the back part of the firebox. 90

An apertured plate 30 is secured to the outer sheet of the backhead 10, and extends downwardly to the deck 12. The aperture 31 of this plate defines the hand firing opening 14 in the backhead and to this plate the usual door (not shown) for closing this opening may be attached. The plate 26 is provided at its rearward margin with a downstanding flange 32 which seats against and is attached to the plate 30, thereby firmly securing the 95 plate 26 in position and contributing to the support of the riser conduit. 100

The portion of the chamber enclosed by the offset 16, below the deck 12, is externally open

or without cover, providing for the admission of air to the firebox through the chamber and between the top margin of the offset and the plate 26, this current of air protecting the plate 26 and its supporting flanges 28 against the intense heat developed in the firebox. The riser conduit is made slightly smaller than the cross sectional dimension of this chamber to permit the inflow of a sufficient volume of air for the purpose mentioned.

The offset 16 being formed as a part of the backhead 10 is protected from the heat by the circulation of water therethrough.

15 By the construction described, fuel delivered by mechanical means is brought into the firebox at the same level as if delivered through the usual hand firing opening and is, therefore, at suitable height for distribution 20 over the entire surface of the grate 11. The stoker mechanism, which includes the offset 16, encroaches so slightly upon the firebox space that the effective area of the grate surface is not diminished to such an extent as 25 to appreciably reduce the furnace capacity.

By jointing the fuel transfer conduit directly to the riser conduit, the former may be made without intermediate joints, its rearward end being loosely mounted upon a 30 proper support under the floor of the tender in accordance with common practice.

I claim as my invention:

1. In a locomotive stoker, in combination, 35 a boiler having a hollow backhead, a section of the backhead being inwardly offset to enclose a fuel receiving chamber opening upwardly, a conduit housed within such chamber, its upper end being open, a plate extending laterally from the upper end of 40 the conduit and covering the upper margin of the backhead offset, and means for delivering fuel to and forcing it through the conduit.

2. In a locomotive stoker, in combination, 45 a boiler having a hollow backhead, a section of the backhead being inwardly offset to enclose a fuel receiving chamber opening upwardly, a conduit housed within such chamber, its upper end being open, a plate ex-

tending laterally from the upper end of the 50 conduit over and spaced from the upper margin of the backhead offset, and means for delivering fuel to and forcing it through the conduit.

3. In a locomotive stoker, in combination, 55 a boiler having a hollow backhead, a section of the backhead being inwardly offset to enclose a fuel receiving chamber opening upwardly, a conduit housed within such chamber, its upper end being open, a plate extending laterally from the upper end of the 60 conduit over and spaced from the upper margin of the backhead offset, flanges on such plate for resting upon the offset, and means for delivering fuel to and forcing it 65 through the conduit.

4. In a locomotive stoker, in combination, 70 a boiler having a backhead provided with a hand firing opening, the section of the backhead immediately below such opening being 75 inwardly offset to enclose a fuel receiving chamber opening upwardly, a plate secured to the outer face of the backhead and having an aperture registering with the hand firing opening, the lower margin of its aperture defining the bottom of such opening, such plate terminating above the bottom of the chamber, a tubular conduit extending through the chamber, its lower end facing 80 backwardly below the named plate, and means for delivering fuel to and forcing it 85 through the conduit.

5. In a locomotive stoker, in combination, 90 a boiler having a hollow backhead, a section of the backhead being inwardly offset to enclose a fuel receiving chamber opening upwardly, a conduit housed within such chamber, its upper end being open, a plate extending laterally from the upper end of the conduit over the upper margin of the backhead offset, means for delivering fuel to and forcing it through the conduit, and a steam nozzle located at the rearward side of the upper end of the conduit for delivering steam jets over the surface of the plate. 95

In testimony whereof I affix my signature.

NATHAN M. LOWER.
